UNITED STATES PATENT OFFICE.

EDWARD FRIES, OF MOORES, PENNSYLVANIA.

BOX FOR FORMING MOLDS.

1,345,160.

Specification of Letters Patent. Patented June 29, 1920.

Application filed October 11, 1919. Serial No. 330,075.

To all whom it may concern:

Be it known that I, EDWARD FRIES, a citizen of the United States, and a resident of Moores, county of Delaware, State of Pennsylvania, have invented certain Improvements in Boxes for Forming Molds, of which the following is a specification.

My invention relates to certain improvements in flasks, or boxes, in which a sand 10 mold is made.

The invention is especially adapted for use in making intricate molds, such as locomotive cylinder castings.

One object of the invention is to make a 15 flask, or box, in which the mold is formed, the box being removed from the formed mold.

A further object of the invention is to make the box adjustable so as to allow for 20 the ready removal of the box from the mold.

These objects I attain in the following manner, reference being had to the accompanying drawings, in which:

Figure 1 is a perspective view of my improved box, in which the mold is formed;

Fig. 2 is a sectional view through the box, showing the pattern in position and the mold rammed around the pattern;

Fig. 3 is a view, similar to Fig. 2, showing 30 the box inverted;

Fig. 4 is a perspective view showing the mold on the bottom plate ready to be transferred to the baking oven;

Fig. 5 is a plan view illustrating a modification of the invention;

Fig. 6 is a side view of the box shown in Fig. 5;

Figs. 7 and 8 are side views of the two plates of the box; and

Fig. 9 is a perspective view of one of the wedges.

The box, in the present instance, is rectangular in shape, and consists of two end plates 1-1, flanged as shown and suitably 45 braced by ribs and side plates 2-2, each having bracing ribs. Each side plate has a projecting trunnion 3. These trunnions are engaged by the hooks of a crane so that the flask can be readily handled and inverted.

Bolts 4 secure the end plates to the side 50 plates. Each end plate projects into the flask forming shoulders 5 at each side and located in the flask at each side are plates 6 pivoted to the end plates at 7, as clearly shown in the drawings. Wedges 8 are

driven between the side plates 6 and the sides of the box so as to force the plates firmly against the shoulders 5 of the end plates. This makes a rigid construction in which the mold can be formed. 9 is a plate 60 on which the pattern α is mounted, as shown in Fig. 2, and the sand γ forming the mold is rammed in the box around the pattern α . A plate 10 is located on the mold within the box. Then the box is inverted, as illustrated in Fig. 3, the plate 10 becoming the bottom plate of the mold. When in this position, the wedges 8 are driven out so as to loosen the plates 6, which then swing loosely on their pivots and the box can be 70 bodily removed from the mold, after which the pattern α is withdrawn, leaving the mold γ on the bottom plate 10, as illustrated in Fig. 4. The slings 11 are then attached to the bottom plate. These slings 75 may be made of rods, as illustrated in Fig. 4, or they may be wire cables, depending considerably upon the size of the mold. The slings are then engaged by the cross bar 12 of a crane, as shown in Fig. 4, and the 80 bottom plate, with the mold, is carried to the baking oven when a baked mold is desired, or it may be assembled for casting without baking.

In Figs. 5 to 9, inclusive, I have shown a 85 modification of the invention in which 1^a are the ends of the box and 2^a are the sides. 6^a are the plates located within the box. Between projections 13 on the back of the plates and the sides 2^a are wedges 14. These 90 wedges extend, in the present instance, the full depth of the box and retain the plates in the fixed position against the pressure of the sand rammed around the pattern. After the sand is rammed and the bottom plate 95 placed in position the box is inverted and the wedges driven out so as to loosen the plates 6^a and allow for the ready withdrawal of the box from the mold.

The operation is as follows: A box of a 100 proper size is selected for a given casting and the pattern is placed on the plate 9. The plate is recessed to receive the projecting hinge portions of the plate 6, as clearly shown in the drawings. The box is placed 105 upon the plate 9 and the wedges 8 are driven so as to force the plate 6 against the shoulders 5 of the box, making a rigid support for the center of the mold, which is then rammed around the pattern. The plate 10 110

is then placed in position on the mold and clamped to the box. The hooks of a crane then engage the trunnions 3 and the box, with the pattern, mold and plate, is lifted, 5 leaving the plate 9 on the molding floor. Then the box is turned on the trunnions and the plate 10 becomes the bottom plate. The wedges and clamps are removed, leaving the plates 6 to swing on their pivots so that 10 when the box is raised it will be withdrawn from the mold, which rests on the bottom plate 10, after which the pattern is withdrawn. The slings 11 are then attached to the bottom plate and the cross bar of a 15 crane is hooked onto the slings and the plate, with the mold thereon, is conveyed to the baking oven. After the mold has been baked a sufficient length of time any cores that are to be assembled on the mold are 20 placed in position, the mold not being enclosed by a flask but open so that the cores can be properly located. Then the mold is placed in a suitable flask and a casting is made.

25 It will be seen by the above construction that a single box can be used for any number of molds, as the box is only used to form the mold. This box is removed from the mold when formed, therefore, fewer 30 flasks are required, with the result that the molding floor is not overcrowded with flasks.

Furthermore, the boxes are not subjected 35 to heat and, consequently, are not destroyed, as is the case where flasks are used in which the mold is made and which inclose the mold during the baking and casting operation.

In some instances, the plate 10 may extend into the box so as to insure a neat fit 40 between the box and the plate. While I have shown two pivoted side plates, a box may be provided with one fixed side plate and one movable side plate to allow the box to be withdrawn from the mold.

I claim:

1. The combination of a box in which a 45 mold is formed, said box having permanent side and end walls and movable side plates located within the box; and means for adjusting said movable side plates without disturbing the permanent structure of 50 the box.

2. The combination of a box in which a mold is formed, side plates pivotally mounted within the box; and means for holding the said pivoted side plates rigid while the 55 mold is being formed.

3. The combination of a box having rigid side plates and end walls; pivoted side plates located within the box, the pivots being at one end; shoulders on the end walls 60 against which the pivoted plates rest; and means for holding the side plates against the shoulders while the mold is being formed.

4. The combination of a box having 65 permanent side and end walls, a movable side plate within the box; and wedges located between the said movable side plate and one of the permanent sides of the mold.

5. The combination of a box for forming 70 a mold, said box having rigid end and side walls, each end wall having shoulders at each side of the center; plates pivotally mounted at one end to the end walls so as to swing freely within the box; wedges engaging the opposite end of the plates for 75 retaining the said plates rigidly against the shoulders of the end walls; a pattern plate recessed to receive the pivot portions of the side plates and having a surface to receive 80 the pattern; and a bottom plate clamped to the other end of the box on top of the mold when formed, said plate forming a supporting bottom plate for the mold when inverted.

EDWARD FRIES.
